TUFTING MECHANISM

Henry J. Schomer, Oshkosh, Wis., assignor to
 Waite Carpet Company, Oshkosh, Wis., a corporation of Wisconsin

Application March 3, 1934, Serial No. 713,836

11 Claims. (Cl. 112—79)

This invention relates to tufting mechanism adapted to be incorporated into a sewing machine for the purpose of drawing out the threads in a series of loops and cutting the same to form 5 tufts, so that the resulting product will exhibit the characteristics of a tufted rug.

The mechanism of the present invention is designed as a modification in the structure of a sewing machine of standard form equipped with 10 means for introducing the loops from a needle over the tip of an oscillating combined looper and cutter along which the succeeding loops will be crowded by the feeding movements of the fabric and ultimately severed and released in the form 15 of tufts which constitute the exposed pile surface of the completed rug.

The oscillating looper of the present invention is designed to operate with an oscillatory needle, which swings forwardly during the feeding of the 20 fabric and backwardly on the upward movement of the needle, although the looper and cutter may be employed with a machine in which the needle has a straight line reciprocatory movement.

25 In certain previous tufting machines with which I am familiar, a stationary looper and cutter has been employed in association with an oscillating reciprocatory needle, but in such cases the cutting of the loops is effected entirely by the 30 slipping of the loops along the edge of the stationary cutter, which requires that the cutting edge be kept extremely sharp at all times, and precludes the use of heavy or tough yarn, which is not easily severed. By combining the cutter 35 with the oscillating head which carries the looper I am enabled to secure the advantage of a positively movable cutter which is more effective for certain classes of work than the stationary cutter previously referred to. In addition to the advantage derived from mounting the cutter on the 40 oscillating head I make provision for the positive rotation of the cutter, which is in the form of a thin disk or wheel, so that the cutting operation will be effectively performed at all times. At the 45 same time, by mounting the looper and cutter on the oscillatory head, the mechanism is rendered extremely compact and simple in construction and sufficiently rugged to withstand hard usage 50 for a long period of time.

Further details and advantages will appear from a description of the invention in conjunction with the accompanying drawings, wherein.—

Figure 1 is a side elevation partially sectioned 55 of a sewing machine of the Singer type, employ-

ing the looper and cutter of the present invention;

Fig. 2 is a front elevation of the machine;

Fig. 3 is a cross sectional elevation through the rear standard of the sewing machine;

5 Figs. 4, 5, and 6 are views of the combined looper and cutter associated with the needle, showing three positions in the cycle of operations;

Fig. 7 is a sectional elevation taken on line 7 of Fig. 4, showing the parts in the positions illustrated in Fig. 4;

Fig. 8 is a similar view showing the parts in the positions illustrated in Fig. 5;

Fig. 9 is a similar view, showing the parts in 15 the position illustrated in Fig. 6; and

Fig. 10 is a similar view illustrating the coaction between the needle and the needle guide block.

The present invention is shown in association 20 with a sewing machine comprising a base or platform 20, provided at its rear end with a hollow standard 21 which carries a forwardly extending arm 22 terminating in a head 23 which encloses the mechanism for reciprocating and oscillating the needle; but in view of the fact that these 25 parts are of standard sewing machine construction constituting a well known type of Singer sewing machine, it is not deemed necessary to describe the mechanism provided for actuating the needle. Such mechanism is operated by a shaft 30, 24, provided near its rear end with a crank 25, and provided beyond the standard with a pulley 26 adapted to be operated from a suitable source 30 of power.

The needle 27 is carried by a rod 28, and the 35 needle operates through a presser foot 29 secured to the lower end of a rod 30 suitably actuated to afford the necessary feeding movements to the fabric in a manner well understood in the sewing machine art.

40 Below the platform 20 are located the parts which more especially form the subject matter of the present invention. These parts include a disk-shaped oscillating head 31 provided on its rear face with spaced lugs 32 furnishing a chuck 45 for engagement with the squared head 33 on the forward end of an oscillating shaft 34 provided at its rear end with an arm 35 which is connected by a pivot 36 with a slide block 37 operating within a slot 38 in a lever 39, which is pivoted upon a pintle 40 and has its opposite end 41 pivoted to a pitman 42 operating on the crank shaft 25.

45 The relationship of the parts is such that continued rotary movement of the shaft 24 will be 50 55

Operation

- transformed into a rocking movement of the lever 39, which in turn will be imparted through the arm 35 to the shaft 34, so that oscillatory movements will be imparted to the oscillating head 31 in properly timed relation to the movements of the needle. Obviously other mechanical connections of an equivalent nature might be employed for imparting the necessary movements to the needle and to the oscillating head.
- 10 The circular oscillating head within its rim is cut away to afford a curved slot 43, leaving the rim 44 in the form of a hook or bill-shaped looper which extends throughout a little more than one-half the circumference of the circular oscillating head, and is provided at its forward or free end with a hooked tip 45, the configuration of the looper being that of a slender curved finger.
- 15 In front of the tip of the looper the metal is cut away to afford a gap 46 which permits the needle to enter, and immediately opposite the gap is located a needle guide block 47 which is screwed or otherwise secured to the uncut center portion 48 of the oscillating head. The guide block is rounded on its inner face to permit the point of the needle to contact and slip by the block in order to bring the needle on each of its reciprocations into exact relation to the tip of the looper. The needle is provided with the usual eye 49 and is cut away or scarfed at the point 50 adjacent to the eye so as to afford a clearance between the needle and the loop of yarn 51 for the entrance of the tip end of the looper when the needle is properly positioned.
- 20 25 30 35 At the rear end of the base of the slot 43 is located a circular or disk-shaped cutter 52, which is keyed upon a pintle 53 journaled by a bracket 54 which is rigidly secured to the oscillating head. The pintle has keyed thereto a pinion 55 which meshes with a stationary pinion 56, the arrangement being such that the pinion 55 will oscillate with the head and ride upon the stationary pinion 56, so that during such movements, rotation will be imparted to the cutter disk in a direction corresponding in each instance to the back and forth or oscillatory movements imparted to the oscillating head as a whole.
- 40 The oscillating head is journaled within a circular recess 57 in a journal head casting 58, which is secured by screws 59 to lugs 60 which depend from the base or platform 20 constituting part of the main frame of the machine. The front face of the casting is extended or thickened in the form of a boss 61, which partially embraces the periphery of the oscillating head and is rabbeted at the point 62 to afford an outer shoulder, which in conjunction with a split guide ring 63 furnishes a guideway for the oscillations of the head. The split guide ring is clamped in place by spring prongs 64 which unite in a spring head 65 which is held in clamping relation by a screw 66.
- 45 50 55 60 65 The stationary pinion 56 is keyed upon a pin 67 which extends inwardly from a bracket arm 68 secured to the boss 61 and extending inwardly toward the center thereof. The inner end of the pin 67 is centered within a recess 69 in the front face of the oscillating head and concentric with its axis of oscillation, so that as the head oscillates, the pinion 56 will remain fixed and stationary and thus afford the means for imparting rotative movements to the pinion 55 and the cutter disk 52 associated therewith.

In the operation of the device we may assume that the parts stand in the position shown in Fig. 4 with the needle elevated and with the oscillating head in its extreme position of clockwise movement. This illustrates a position in which the rotating cutter disk 52 has just severed the next preceding loop in advance of the one last discharged from the needle. Thereafter the oscillating head will move in a counter-clockwise direction to the extreme position shown in Fig. 6 and through the position illustrated in Fig. 5.

Fig. 5 shows the parts in an intermediate position with the needle piercing the fabric and approaching the looper. In Fig. 6 the tip of the looper has swung past the needle but still retains the last preceding loop of yarn in uncut condition, and with the parts thus positioned the tip of the needle will lie against the curved guide block 47 and be held against displacement as the tip of the looper begins to move to the right and through the space afforded by the scarf in the needle, so that at the beginning of the clockwise stroke a new loop will be engaged. Such engagement is also facilitated by the forward swing of the oscillatory needle in the particular embodiment shown, although in cases where a straight line reciprocating needle is employed the mode of operation is not essentially different.

During the continued movement of the oscillating head in clockwise direction, the two uncut loops will stand in adjacent relation to one another until the rotary cutter disk engages the foremost loop and cuts it and comes to rest in the position shown in Fig. 4 preparatory to the next operation. In order to cause the rotating disk to act most effectively in severing the loops, and in order to guide its cutting edge, the looper is longitudinally slotted at the point adjacent to the periphery of the cutter disk, so that the disk will thus act through the looper and engage that portion of each of the loops which bridges or spans across the inner face of the looper, which thus holds this portion of the loop in taut condition during the advance of the rotating cutter toward the loop.

By forming the looper in the manner shown and by giving it an arcuate configuration concentric of its axis of oscillatory movement, the looper may be made of sufficient length to easily accommodate the operations last described, and to permit the rotating cutter, with its operating train, to be mounted in the manner described. It will be understood that during its oscillatory movements, the looper will slip through the uncut loops and at all times hold the same in taut condition until the arrival of the cutter and the severance of the foremost loop. This method of severing the loops is advantageous in that it relieves the loops from the tension which might otherwise be occasioned during the cutting operation, so that each loop will be easily severed without tending to pull out or disturb the loop arrangement, even though somewhat heavy and tough yarn be employed in the stitching of the tufts.

The device as a whole is extremely compact, and the parts constituting the present invention are in the form of a self-contained unit which may be readily applied to or removed from a sewing machine of standard construction, with but slight rearrangement, and in view of the fact that all of the operating parts are carried within a small compass, the danger of maladjustment is reduced.

to a minimum, and the parts are properly held and reinforced to permit of rapid operation under conditions which require extreme precision in order to insure the proper timing relation and proper presentation of the looper to the eye of the needle.

Although the device has been described with considerable particularity as to detail, it is not the intention, unless otherwise indicated in the claims, to limit the construction to the details shown, since modifications thereof may be made without departing from the spirit of the invention.

I claim:

1. In a tufting machine of the class described, the combination of a reciprocating needle, an oscillating head and means for affording oscillatory movements thereto in timed relation to the movements of the needle, said head having a portion of its periphery configured in the form of a bill-shaped looper, a rotating loop cutter carried by the oscillating head, and means for rotating the cutter.

2. In a tufting machine of the class described, the combination of a reciprocating needle, an oscillating head and means for affording oscillatory movements thereto in timed relation to the movements of the needle, said head having a portion of its periphery configured in the form of a bill-shaped looper, a rotating loop cutter carried by the oscillating head, and means actuated by the oscillations of the oscillating head for rotating the cutter.

3. In a tufting machine of the class described, the combination of a reciprocating needle, an oscillating head and means for affording oscillatory movements thereto in timed relation to the movements of the needle, said head having a portion of its periphery configured in the form of a bill-shaped looper, a rotating loop cutter carried by the oscillating head, and a gear train actuated by the oscillations of the oscillating head for rotating the cutter.

4. In a tufting machine of the class described, the combination of a reciprocating needle, an oscillating head and means for affording oscillatory movements thereto in timed relation to the movements of the needle, said head having a portion of its periphery configured in the form of a bill-shaped looper, a rotating loop cutter carried by the oscillating head, and a gear train for rotating the cutter including a fixed pinion mounted concentrically with respect to the oscillating head and an intermeshing pinion fixedly connected to and movable with the rotating cutter.

5. In tufting mechanism of the class described, the combination of a reciprocating needle, a circular oscillating head and means for imparting oscillations thereto in timed relation to the movements of the needle, said head being cut away on its interior to afford an arc-shaped looper around a portion of its periphery, and a rotating cutter journaled upon and movable with the oscillating head into position to sever loops engaged by the looper, and means for imparting rotation to the cutter.

6. In tufting mechanism of the class described, the combination of a reciprocating needle, a circular oscillating head and means for imparting oscillations thereto in timed relation to the movements of the needle, said head being cut away on its interior to afford an arc-shaped looper around a portion of its periphery, and a rotating cutter

journaled upon and movable with the oscillating head into position to sever loops engaged by the looper, and means for imparting rotation to the cutter, said means being actuated by the oscillations of the oscillating head.

7. In tufting mechanism of the class described, the combination of a reciprocating needle, a circular oscillating head and means for imparting oscillations thereto in timed relation to the movements of the needle, said head being cut away on its interior to afford an arc-shaped looper around a portion of its periphery, and a rotating cutter journaled upon and movable with the oscillating head into position to sever loops engaged by the looper, and means for imparting rotation to the cutter, said means being actuated by the oscillations of the oscillating head and including a pinion carried by the rotating cutter and a fixed center pinion with which the former pinion meshes. 20

8. In tufting mechanism of the class described, the combination of a reciprocating needle, a circular oscillating head and means for imparting oscillations thereto in timed relation to the movements of the needle, said head being cut away on its interior to afford an arc-shaped looper around a portion of its periphery, and a rotating cutter journaled upon and movable with the oscillating head into position to sever loops engaged by the looper, and means for imparting rotation to the cutter, said means being actuated by the oscillations of the oscillating head and including a pinion carried by the rotating cutter and a fixed center pinion with which the former pinion meshes, the looper being slotted adjacent to the rotating cutter to permit the edge thereof to project through the looper to sever loops while distended thereby. 30

9. In tufting mechanism of the class described, the combination of a reciprocating needle, a looper mounted to bring its free end toward and from the needle to engage and carry loops discharged from the needle, and a rotating cutter carried by the movable looper and adapted on each forward advance of the looper to sever the foremost loop engaged by the looper, and means for rotating the cutter including a pinion carried by the cutter and a fixedly mouthed toothed member with which said pinion meshes. 40

10. In tufting mechanism of the class described, the combination of a reciprocating needle, a movable looper mounted to bring its free end toward and from the needle to engage and carry loops discharged from the needle, and a rotating cutter wheel journaled on and movable with the movable looper and adapted on each forward advance of the looper to sever the foremost loop engaged by the looper, and means for rotating the cutter wheel concurrently with its forward movement. 50

11. In tufting mechanism of the class described, the combination of a reciprocating needle, a movable looper mounted to bring its free end toward and from the needle to engage and carry loops discharged from the needle, and a rotating cutter wheel journaled on and movable with the movable looper and adapted on each forward advance of the looper to sever the foremost loop engaged by the looper, and means actuated by the movements of the looper for rotating the cutter concurrently with its forward movement. 65
